TRAIN-CONTROL APPARATUS.

Substitute for abandoned application Serial No. 454,684, filed March 23, 1921. This application filed February 14, 1928. Serial No. 254,312.

My present invention relates to the train control system as set forth in my application Serial No. 284,731, filed March 24, 1919, and concerns additions to such a system to enable 5 the engineer to exert control to meet certain requirements of operation as will be described hereinafter.

This application is a substitute for my application, Serial No. 454,684, filed March 23, 10 1921, and abandoned.

In the drawings:

Figure 1 is a diagrammatic view of the system;

Fig. 2 is a vertical sectional view of a speed 15 governor valve and timing mechanism;

Fig. 3 is a sectional view of the parts of Fig. 2 taken at right angles to the plane of Fig. 2;

Fig. 4 is a view of a detail;

20 Fig. 4^a is a sectional view of a modified form of timing means;

Fig. 5 is a vertical sectional view of the 25 disabling valve and operating mechanism, with the valve in normal, or in other words, open position, to allow pressure to go to the train pipe;

Fig. 6 is a horizontal sectional view on the line 6—6 of Fig. 5;

Fig. 7 is a vertical sectional view of the 30 valve in its closed position;

Fig. 8 is a sectional view a quarter turn from that shown in Fig. 7;

Fig. 9 is a view of the engineer's automatic 35 brake valve H⁶ with an attachment as employed by me, like in the application referred to.

One object of the invention is to permit the engineer when he has brought his train down to a prescribed slow speed of control, to 40 eliminate the function of a ramp operable automatic brake applying system so that he can run by the caution board or stop board with his brakes free. The means for exerting this control is operable by hand independently of the engineer's automatic brake 45 valve such as the valve H⁶ of the Westinghouse system.

This independent control means is in turn controlled by a speed governor so that the 50 eliminating of the ramp operated automatic brake applying system cannot be effected except by the operation of the engineer's auto-

matic brake valve when running at a speed 55 above the control speed or above the prescribed low speed, and on the other hand, the eliminating action cannot be effected by the independent hand operable means except when the train is running within control, viz, at the prescribed slow speed.

Timing means are also provided whereby 60 when the engineer operates the said independently operable hand device to eliminate the function of the automatic ramp operated means, the timing means will maintain the eliminating valve in set position for a period 65 of time to pass the ramp and for certain actions to transpire as will be hereinafter described.

Other objects will be pointed out hereinafter.

In the drawings 1 indicates the roller on the engine which by striking a ramp alongside the track causes the automatic setting of the brakes.

19 is the trigger valve which is operated by 75 air when the roller 1 is lifted, so that said valve will be set in position to permit air to pass from the equalizing reservoir through pipes 8 and 13 to pipe 15 and thence to the automatic service valve A, so that this will 80 be operated to release air from the train line pipe through the port 44' for setting the brakes automatically; when, as above indicated, the ramp is set to lift the roller 1.

B indicates the disabling valve which is 85 operated by the passage of air through pipe 51 from the casing of the automatic service valve A when this is operated as just mentioned to set the brakes by releasing the air from the train line pipe through port 44', 90 the function of this disabling valve and its time of operation in relation to the operation of valve A being such as to prevent the engineer from recharging the train line pipe by operating the Westinghouse automatic 95 brake valve H⁶, until after a prescribed period of time has elapsed, during which time the train will have come to a stop. This disabling valve in performing its function cuts off communication between the pipes 50 and 50^a and 100 thus as just stated above prevents the engineer from recharging the train line pipe until the prescribed period of time has elapsed. This period of time which must

elapse before the engineer can recharge the train line pipe and thus take off the brakes is due to the fact that the air pressure introduced to the valve casings A and B to operate the valves therein must be bled from these parts before these valves can be restored to normal position and the bleeding effect will not be initiated until pressure has built up in pipe 15 sufficiently, so that, passing to the operating means for resetting the valve 19 this will be turned to cut off communication between the pipes 13 and 15 and open a bleed port at valve 19 so that air pressure will bleed from valve casings A and B and only when this has occurred can the disabling valve in casing B be reset by the engineer sending pressure through pipe 57 from the ordinary Westinghouse independent brake valve S⁶. Pipe 57 extends from the usual exhaust port 20 of valve S⁶.

The automatic system just referred to, and fully described in my application mentioned above, provides for bringing the train to a full stop and presupposes that the engineer is 25 incapacitated or is negligent.

These instances are comparatively rare and as set forth in the application referred to, means are included in the present system whereby the engineer on approaching a caution signal may continue running his train provided he is alert and paying attention to his work and slows down the speed of the train upon running into a danger zone.

This means as in the application referred 35 to, includes an eliminating valve B' interposed in the pipe 15 and adapted when operated to eliminate the function of the automatic service valve A and the disabling valve B. This valve is operated to perform its 40 eliminating function by pressure admitted thereto from the Westinghouse automatic brake valve H⁶ when the handle of said valve is operated to secure a Westinghouse application of the brakes. In the system described 45 in said application, the air pressure from valve H⁶ is supplied to the eliminating valve by a pipe 52, and when this valve is operated by this air pressure it eliminates the function of the automatic system because this is not 50 now necessary, owing to the fact that the engineer is performing his duty by applying the brakes by valves H⁶ the brake pressure escaping through the port marked B. P. Ex., i. e., brake pipe exhaust.

The eliminating action, i. e., cutting out the automatic operation of the automatic stop system, can take place in the apparatus described in my previous application, and as 60 thus far described herein, only when the engineer places the automatic brake valve H⁶ in service position and consequently only when a Westinghouse application of the brakes is effected by operating the valve H⁶.

There are times, however, when it is desirable 65 or rather necessary to eliminate the ac-

tion of the automatic system in order to comply with the rules governing the action of the engineers.

For instance, there is a rule laid down by the railroads that when a caution signal is 70 displayed the engineer must bring his train under control by reducing speed without coming to a stop, so that he may be able to stop quickly on reaching a stop signal.

There is a further rule that when the speed 75 of a train is low, say, ten miles an hour, and an application of the brakes is made, the application must be maintained until the train comes to a full stop. The latter rule exists because damage is liable to result if the brakes are released while the train is running at the low speed stated, this damage being due to the buckling of the train or to the pulling of a draw head, resulting from the jerking of one car upon another.

My present improvement includes as one of its features means whereby the function of the automatic system may be eliminated without operating the handle of valve H⁶ and consequently without making a Westinghouse application of the brakes, so that, if the train

is running at the low speed stated, or instance, ten miles an hour, which is under control, the engineer can pass a ramp at the approach indication without having the brakes applied by said ramp automatically and without setting the brakes by a Westinghouse application, so that the train may continue at the slow speed with its brakes off and without violating the rule above stated of coming 100 to a full stop consequent upon the existence of the two conditions, i. e. brakes applied and slow speed.

I have therefore provided means whereby the function of the automatic brake system 105 can be eliminated entirely independently of the operation of the valve H⁶ and with the train running free at the stated slow speed.

This means consists of what I term for convenience an automatic speed control valve 110 interposed between the automatic brake valve H⁶ and the eliminating valve B' and controlling the supply of air to the latter.

This valve C consists of a sliding rod having a port 59 which is adapted to register with either of the passages 60, 61 of the valve casing to permit the passage of air to the pipe 52^a, leading to the eliminating valve B' to set it in eliminating position, is being understood that this eliminating valve is normally held open and is returned to its open position, when air pressure is taken off, by a spring. Air is supplied to the passage 60 by a pipe 52^b from chamber D of the ordinary Westinghouse automatic brake valve H⁶ through a plug valve 58 in a branch pipe 52^c of the pipe 52^b. The position of the valve C is controlled by a speed governor, consisting of balls 62 on arms 63 connected to the valve rod and to a shaft 64 of a bevel gear 65 which 120

is driven by gears 66, 67 from a flexible shaft 68 driven from the wheel 69 of the pony truck. The valve rod has a reduced end sliding in the shaft with a spring 70 for pressing the valve normally upward to make its port 59 align with passage 60 which receives air pressure through the pipes 52^a and 52^b from chamber D of the automatic brake valve H^e when plug valve 58 is opened. This valve is opened by a lever 71 which is operated by a push button 72. The valve is closed by a plunger 73 pressed by a spring 74, this plunger having a valve 75 at its lower end which when the push button is pressed, admits air from the pipe 52^b and the branch 52^a. This air passes through a passage 83 to a vane wheel 76 and turns the same, and this vane wheel has its shaft 77 provided with a gear 78 meshing with a gear 79 on the same shaft 80 with a cam 81 having a recess or low part 82 which normally receives the end of the lever 71.

Supposing now that the train is running at the prescribed slow speed which insures the control by the engineer to effect a quick stop, if necessary, say, at ten miles an hour, and the train approaches a caution signal, the engineer does not want to have the brakes applied automatically by the ramp, nor does he want to apply them by making a Westinghouse application by operating automatic brake valve H^e. On the contrary, he wants to pass the caution signal at the slow speed stated and without applying the brakes, because if the latter effect happened, he knows that he must come to a full stop in order to obey the rule against thereafter releasing the brakes at said slow speed.

He, therefore, does not manipulate valve H^e but simply pushes button 72 before the ramp is reached. This will operate lever 71, open plug valve 58 and allow air pressure to pass from chamber D of the valve H^e through pipe 52^e to passage 60, and, because of the slow speed at which the train is running, the governors 62, 63 will be holding the slide valve C up with its port 59 in line with passage 60 and therefore air pressure will pass from passage 60 through pipe 52^a to the eliminating valve and the same will be forced down against the pressure of its spring and the eliminating valve will close communication through pipe 15 to the automatic service valve A and also the disabling valve B and the automatic system will be prevented from operating, despite the fact that the roller 1 will have been lifted by the ramp, which, of course, it set in operative position when the caution board is set. Therefore the train can continue past this station running at the prescribed slow speed and with its brakes free.

The same action of pressing down the button, just described, will open valve 75 and allow air to pass to the vane wheel rotating

the same and turning the cam 81 in the arrow direction so that its high part will hold the lever 71 in its operated position with the valve 58 open and with the valve 75 also open until the low part 82 of the cam comes under the lever, when the spring 74 will operate the lever to close both valves 58 and 75, thus completing one cycle of operation of the timing mechanism. The closing of valve 58 will cut off air pressure from the eliminating valve which will then be restored to open position by its spring, the air passing out from pipe 52^a through any suitable leakage space, for instance, along the stem of valve C, which is loose enough in its slide bearings to allow this, but not loose enough to prevent delivery of high pressure to the eliminating valve. This cycle of operation of the timing mechanism is sufficient in duration to permit the roller 1 to pass the ramp and also to permit the valve 19 to be reset by the building up of pressure in pipe 15 before the eliminating valve is again opened. It will be understood that when the eliminating valve B' is closed pressure immediately builds up in pipe 15 and this will restore the valve 19 to normal position. Should the next signal still be a caution signal, the engineer can press the button and the above operations will be repeated. Should the next signal be "clear" the engineer can speed up and this action will violate no rule, his brakes not having been applied and there being therefore no necessity for their release while running slow.

The operations above described will not interfere with the engineer in stopping the train at any time by operating automatic brake valve H^e and getting a Westinghouse application of the brakes by exhausting the air at B. P. Ex.

As above pointed out, the pipe 52 leading from the automatic brake valve H^e connects with the passage 61 of the automatic speed control valve and it will be observed that, when the train is running at a prescribed low speed, this passage and pipe 52 will be closed, because the valve C will be standing in slow speed position with its port 59 in line with passage 60. The engineer therefore in order to eliminate the automatic system is forced to push the button. He cannot eliminate by operating the handle of automatic brake valve H^e because the pipe 52 leading therefrom is shut off by valve C.

High speed.—If the train is running at high speed or at a speed above the prescribed low speed of say, ten miles an hour, the valve C will be moved by the governor so that the passage 61 will be opened. The engineer can then eliminate the functions of the automatic system when he makes a Westinghouse application of the brakes by operating the automatic brake valve H^e because the air pressure is then free to pass through the pipe 15.

52 to passage 61 and pipe 52^a to the eliminating valve. In this action the air to pipe 52 is supplied from a supplemental valve casing *h*, Fig. 9, on the casing of engineer's valve H⁶ having a supplemental valve *h*². This valve is held on its seat by main reservoir pressure and a spring. A cam member *h*³ on the handle of this valve H⁶ rides over a ball on the fluted stem of the supplemental valve *h*² to force it from its seat, when handle *h*⁵ of the valve H⁶ is turned into position to slow down the train and then air pressure will pass from the space *h*⁶ to pipe 52 and to eliminating valve B' to prevent the operation of valves A and B. If, after having placed valve H⁶ in service position to slow down the speed, the engineer, by reason of becoming incapacitated, or for any other reason, should put the handle of this valve out of service position, the air will be taken off from the eliminating valve and the spring of this valve will open it and allow air pressure to pass to the valves A and B when the roller 1 is lifted by contacting with the ramp, with the result that the train will be stopped automatically.

The taking off of air from the eliminating valve when the valve H⁶ is put out of service position, i. e., when valve *h*² closes, will be due to leakage past the ball *h*⁴ from pipe 52 to atmosphere.

Having applied the brakes as just stated, if the engineer wants to run by the caution board with the brakes off in order to continue running slow and avoid a complete stop, he can watch the speedometer and when this shows that the speed of the train has been reduced to the point of quick control before reaching the ramp and that the governor has set the valve C to open passage 60, he places the handle of valve H⁶ either in release or running position, thus releasing the brakes. He then pushes the button 72 so that pressure will be continued on the eliminating valve through port 60, instead of through port 61.

Having applied the brakes as just stated, if the engineer wants to run into the caution block with the brakes off in order to continue running slow and avoid a complete stop, after roller 1 passes the ramp, he can watch the speedometer and when this shows that the speed of the train has been reduced to the point of quick control, and consequently that the governor has set the valve C to open passage 60 he will first push the button so that the eliminating valve will be subjected to the pressure from chamber D as above described, and this will be maintained in eliminating position closing pipe 15, and having done this the engineer can set his automatic brake valve H⁶ either in release or running position again, thus releasing the brakes, so that the train may continue running at the prescribed slow speed.

The pressing of the button in the action

just described before operating the automatic brake valve H⁶ to running position is necessary, because were the brakes taken off first and had the valve 19 not been given time to be restored to normal position, the setting of the valve H⁶ in running position would have cut off air pressure from eliminating valve B' and this would have been reset to open position by its spring and consequently the air pressure could pass from valve 19 through the eliminating valve to the automatic service valve A with the result that the brakes would again be applied.

The train would then be brought to a full stop by this automatic system despite the control of the engineer. This result would be forced upon the engineer contrary to his wishes, but if he had pressed the button before he took the handle of the H⁶ brake out of service position, he would have put pressure against the eliminating valve, holding it shut so that if valve 19 had not completed its operation it would not affect valve A and disabling valve B.

I have provided means whereby the speed of the train may be prevented from exceeding that predetermined upon.

This consists of a valve 76^x closing a port 77^x leading to the atmosphere from a branch pipe 52^b which connects with the pipe 52^a leading to chamber D. This valve is operated by the speed controlled valve but through a lost motion connection formed by the valve stem having a head 78^x in a cylinder 79^x of the speed controlled valve. As the speed controlled valve moves down upon the increase of speed of the train, the head 78^x will be contacted by the upper end of the cylinder of the speed controlled valve when this reaches a position corresponding to the maximum speed predetermined upon beyond which the train must not go. When this contact takes place, the valve 76^x will be opened to discharge the air and thus effect the application of the brakes. The valve is adjustable so that it will be operated at different points in the movement of the speed controlled valve according to the maximum speed determined upon, and for this adjustment one side of the valve casing is removable so that access may be had to the screw 80^x by which the valve stem may be set in relation to the valve, so that the head 78 will be struck sooner or later according to the speed desired. The valve is pressed up against its seat by a spring 81^x.

A speedometer is shown at 82^x driven from the flexible shaft 68 through gearing 66 and 67 and shaft 83^x.

I have improved the construction and operation of the disabling valve.

The valve comprises a casing B^a having pipe 50 connected at its upper end, leading main reservoir pressure thereto from the engineer's automatic brake valve H⁶ (Westinghouse), and having pipe 50^a connected at

its lower end and leading to the train pipe. The valve comprises two members 85, 85^a, of disc form, adapted to seat at 85' within the casing. The member 85 seats in the direction 5 of pressure from the main reservoir through pipe 50 and the valve member 85^a seats in the direction of pressure from the train pipe through the pipe 50^a; and a positive seat is provided in both instances with the pressure 10 back of the valves and acting in a direction axially thereof to hold them firmly to their seats.

Each valve has a stem 86 guided in a collar 87 screw threaded into an interior casing 88 15 which is clamped in place between the head B'' of the valve casing and the main part of the said casing.

Each valve stem has a head 89 on its inner end. Between these heads is located a rocking member 90 on a shaft 91 journalled in the main casing of the valve and having an arm 92 connected by links 93, 94, with pistons 95, 96 one of which is located in a cylinder 57^x connected with the pipe 57 leading from the 20 engineer's independent brake valve S^e, and the other piston 96 is located in a cylinder 51^x which is in connection with the cylinder 51' which in turn connects with pipe 51 leading from the automatic service valve A.

Supposing the valve to be open as in Fig. 5 and that an automatic application of the brakes takes place, the air pressure upon operating automatic service valve A and before this has been completely operated to release train pipe pressure, as above described, through port 44' for setting the brakes, will pass through pipe 51 and will move the piston 51'' in cylinder 51' against the pressure of its spring 97, and this will result in uncovering port 98, thus allowing air from pipe 51 to reach the piston 96, moving this leftward, and thus through the link and arm 92, turning the rocker arm 90 from its position shown in Fig. 5, where it is holding the valve members open, to the cross-wise position shown in Fig. 7, which will allow the springs 99 to close the valve members upon their seats, thus effectually closing all communication between the engineer's automatic brake valve H^e and the train pipe, so that the engineer cannot recharge the train pipe and release the brakes until after a prescribed period of time has elapsed, during which period the train will have lowered its speed to the point where 55 it is well under the control of the engineer or has stopped.

Describing more in detail the action just described, it will be noted that the movement of the piston 51'' leftward will first operate a 60 detent 100 pivoted on the cylinder casing and withdraw this detent from the notch 101 of the piston 96, so this will be free to move leftward under the pressure of air admitted through the port 98. Up to this time, however, the piston 96 has been held locked, in

the position shown in Fig. 5, by the detent, and consequently, the rocker arm 90 is held firmly locked to maintain the valve members in open position. Under this condition, no jar or vibration due to the running of the 70 train or bumping of cars will have any effect in displacing the valve members, which will maintain their open positions. The leftward movement of the piston 51'' will bring its shoulder 51^a into position to be engaged by the 75 upper end of the detent under action of the spring 51^b and therefore the piston 51'' will be held locked in its operated position at the left of the cylinder and as illustrated in Fig. 7. This locking of the piston 51'' in its leftward position will maintain port 98 open, and therefore the air pressure in bleeding out through pipe 51, automatic service valve A, pipe 15, and trigger valve, as above described, 80 will reduce the air pressure in cylinder 51^x to atmosphere and then when air pressure is introduced from engineer's valve S^e, through pipe 57 into cylinder 57^x and acts on the piston 95, this will be moved towards the right 85 and through the link and lever the rocking 90 cross arm will be turned from the position shown in Fig. 7 to that shown in Fig. 5, to open both of the valve members against the tension of their springs, and thus place this 95 valve organization in condition to afford communication between the engineer's automatic brake valve H^e and the train pipe through pipes 50, 50^a, so that the train pipe can be recharged and the brakes released when the engineer so desires, or by operating his valve 100 H^e the engineer can apply the brakes without interference by this disabling valve, which is now, as stated, held open or in normal condition.

In moving towards the right from the position of Fig. 7, during the opening of the valve, the piston 96 will work against the cam edge 100' of the detent 100 and withdraw this detent from the shoulder 51^a of the piston 51', and the spring of this piston will then move 110 it to the right ready for another action, and when the parts are again in normal open position the detent will lock piston 96 and prevent jar or shock from having any effect on the valve mechanism which might displace 115 the valve members.

It will be noted that the valve operating mechanism in closed position receives the pressure directly on the valve members and these members are held firmly on their seats 120 so that no vibration can dislodge them. The valve members are therefore held locked in open position by the detent and in closed position they are held seated by the pressure.

The inner casing of the valve frame is perforated at 102 for the passage of air.

The rocking cross arm is adapted to open the lower valve member 85^a first and immediately after this has been opened, the upper valve member will be opened. By reason of 130

this, the operation is rendered easier, because, instead of initiating the action against the pressure on both valves, the pressure on only one valve need be dealt with at first and when 5 this valve member opens, pressure will be equalized on the two sides of the upper valve, and this will then be opened with ease.

At 103 is shown an exhaust port for valve S⁶. This takes the place of the usual exhaust 10 port from valve S⁶ which ordinarily discharges to atmosphere. In the present arrangement, this exhaust port will be closed by piston 95 when the disabling valve is in closed position, as in Fig. 7. When valve S⁶ 15 is operated to deliver air into pipe 57 this will first operate piston 95 and open the disabling valve and then the air pressure will exhaust through port 103 from pipe 57 and valve S⁶, leaving this port open, so that then the engineer 20 may use his S⁶ valve as freely as though pipe 57 were not there.

Instead of employing the form of timing mechanism consisting of the cam 81, the gearing, vane wheel, lever 71 and also the valve 25 58 for admitting air to the pipe 52^c, I may employ the timing mechanism shown in Fig. 4^a, and utilize the valve 75 as the means for admitting air into the pipe 52^c, and thence 30 through port 60 and pipe 52^a, when the engineer is in the position of slow speed shown in full lines of Fig. 2, with the valve port 59 open.

This mechanism consists of a stem 72^a 35 working in the cylinder 84 and having an air tight plunger 85 of cork. The lower end of the stem bears on the top of valve 75, and when depressed moves the valve from its seat to admit air pressure into the pipe 52^c directly, and from the pipe 52^b. At the same time a 40 piston 86 in the larger cylinder 87 moves down, it being connected with the stem, and this piston forces air out of the cylinder through the port 88 controlled as to its size by the pin 89, suitably adjustable. When pressure 45 of the hand is relieved from button 72, the piston rises under the pressure of the spring of valve 75 under control of air slowly admitted through small port 88, and hence valve 75 will be held open for the prescribed 50 period of time to permit the ramp to be passed, and the eliminating valve B' will be held in eliminating position until the plunger is raised far enough, by the spring of valve 75, to allow valve 75 to close and cut off the air 55 pressure to pipe 52^c. The eliminating valve will then open by its spring, the air above the eliminating valve leaking out around the stem of valve 75.

I claim:

60 1. In a train controlling system, automatic brake applying means to be operated by air pressure, for applying the brakes, an eliminating valve for cutting off the supply of air to said automatic means to eliminate the function thereof when the engineer is attentive

and operates his valve to effect application of the brakes, and controlling means for operating the eliminating valve by the engineer independently of the operation of the engineer's valve, to eliminate the function of the 70 automatic brake applying means when the train is running at a prescribed reduced speed, substantially as described.

2. In a train controlling system automatic brake applying means to be operated by air 75 pressure for applying the brakes, an eliminating valve for cutting off the supply of air to said automatic means, to eliminate the function thereof when the engineer is attentive and operates his valve to effect application of the brakes, and controlling means for operating the eliminating valve by the engineer independently of the operation of the engineer's valve, to eliminate the function of the 80 automatic brake applying means when the train is running at a prescribed reduced speed, and speed governor means for permitting the effective operation of said controlling means at the prescribed slow speed, but preventing said means from effecting the 85 operation of the eliminating valve at higher speeds, substantially as described.

3. In combination, a valve to supply air pressure, automatic brake applying means operated by said air pressure, said valve being adapted to be reset by the building up of pressure beyond it in the automatic system, an eliminating valve between said first mentioned valve and the automatic brake applying means, an automatic brake valve operable by the engineer to set the brakes, and at the same time operate the eliminating valve to cut out the automatic brake applying means, hand operable means independent of the engineer's automatic brake valve for operating the eliminating valve to cut out said automatic brake applying means, a speed governor for rendering the operation of said independent hand operable means effective in setting the eliminating valve in its eliminating position when the train is running at a prescribed slow speed and to prevent said independent means from setting the eliminating valve while the train is running at a higher speed and timing means for maintaining the eliminating valve in its set position for a prescribed period until the valve first mentioned has reset itself, substantially as described.

4. In combination a valve to supply air pressure, automatic brake applying means operated by said air pressure, said valve being adapted to be reset by the building up of pressure beyond it in the automatic system, an eliminating valve between said first mentioned valve and the automatic brake applying means, an automatic brake valve operable by the engineer to set the brakes, and at the same time operate the eliminating valve to cut out the automatic brake applying means,

hand operable means independent of the engineer's automatic brake valve for operating the eliminating valve to cut out said automatic brake applying means, a speed governor for rendering the operation of said independent hand operable means effective in setting the eliminating valve in its eliminating position when the train is running at a prescribed slow speed and to prevent said independent means from setting the eliminating valve while the train is running at a higher speed, and timing means for maintaining the eliminating valve in its set position for a prescribed period until the valve first mentioned has reset itself, said independent means setting the eliminating valve by air and said timing means operating by air, substantially as described.

5. In combination with an air brake system, including an automatic brake valve to be operated by the engineer for setting the brakes, an air pressure operated system for setting the brakes automatically, air pressure operated eliminating means for eliminating the operation of the automatic brake applying system when said automatic brake valve is operated by the engineer, and the train is running at a speed above a prescribed speed, independent hand operable means for supplying air pressure for setting the eliminating valve, when running at a speed below that prescribed, and speed governor means for preventing the setting of the eliminating valve by the engineer's automatic brake valve when the train is running at the low speed and preventing the setting of said eliminating valve by said independent means when the train is running at a speed above that prescribed, substantially as described.

40 6. In combination, an automatic brake valve substantially like the valve H^e of the Westinghouse system, said valve being adapted to apply the brakes when its handle is operated by the engineer, an air pressure operated system for automatically applying the brakes, air pressure operated means for eliminating the function of said automatic system, an air pressure pipe leading to said eliminating means, a speed governor controlled valve controlling the supply of air to said pipe, a pipe leading to said valve to supply air pressure therethrough to said first mentioned pipe when said valve is set in slow speed position by said governor, and a pipe leading to said speed governor controlled valve to supply air pressure therethrough, from the said valve H^e to the pipe first mentioned for setting the eliminating means when the said governor controlled valve has been set in high speed position by the said governor and the valve H^e has been operated to apply the brakes, and means to be operated by the engineer for controlling the air pressure from chamber D to the said governor controlled valve, substantially as described.

7. In combination, an automatic brake valve substantially like the valve H^e of the Westinghouse system, said valve being adapted to apply the brakes when its handle is operated by the engineer, an air pressure operated system for automatically applying the brakes, air pressure operated means for eliminating the function of said automatic system, an air pressure pipe leading to said eliminating means, a speed governor controlled valve controlling the supply of air to said pipe, a pipe leading to said valve to supply air pressure therethrough to said first mentioned pipe, when said valve is set in slow speed position by said governor, and a pipe leading to said speed governor, controlled valve to supply air pressure, therethrough from the said valve H^e to the pipe first mentioned for setting the eliminating means when the said governor controlled valve has been set in high speed position by the said governor and the valve H^e has been operated to apply the brakes, and means to be operated by the engineer for controlling the air pressure from chamber D to the said governor controlled valve, and timing means set in operation by the operation of the last mentioned means to hold said means in operated position for a prescribed period, substantially as described.

8. In combination an automatic brake valve operable by the engineer for setting the brakes, an air pressure system operating automatically for setting the brakes, means for eliminating the function of said automatic system at times said eliminating means being set by air pressure, a speed governor controlled valve for supplying air to said eliminating means, two air pressure supply conduits leading to said governor controlled valve, one for high speed and one for low speed, and means whereby the engineer may permit or prevent the passage of air through said low speed conduit to the governor controlled valve, the said automatic brake valve controlling the passage of air pressure through said high speed conduit, substantially as described.

9. In combination in an air brake system an automatic brake valve H^e to be operated by the engineer for setting the brakes, an air operated means for setting the brakes automatically, a valve C, two conduits 52 and 52^b leading to said valve C, the conduit 52 being supplied with air from valve H^e when the latter is operated by the engineer, an eliminating valve for cutting off air pressure supply to the automatic brake applying means to eliminate the function thereof, a conduit 52^a for supplying air from valve C to the said eliminating valve, a speed governor controlling the position of the valve C to connect conduit 52 with pipe 52^a when the engine is running at a prescribed speed and to connect conduit 52^a with conduit 52^b when the speed is low-

ered, and a valve for controlling the conduit 52^b, said valve being operable by the engineer, substantially as described.

10. In combination in an air brake system
5 an automatic brake valve H^6 to be operated
by the engineer for setting the brakes, an air
operated means for setting the brakes auto-
matically a valve C, two conduits 52 and 52^b
leading to said valve C, the conduit 52 being
10 supplied with air from valve H^6 when the
latter is operated by the engineer, an elimi-
nating valve for cutting off air pressure sup-
ply to the automatic brake applying means to
eliminate the function thereof, a conduit 52^a
15 for supplying air from valve C to the said
eliminating valve, a speed governor control-
ling the position of the valve C to connect
conduit 52 with pipe 52^a when the engine is
running at a prescribed speed and to connect
20 conduit 52^b with conduit 52^a when the speed
is lowered, and a valve for controlling the
conduit 52^b said valve being operable by the
engineer, and timing means operated by air
25 for holding latter valve open for a prescribed
period.

11. In combination in an air brake system an automatic brake valve H^e to be operated by the engineer for setting the brakes, an air operated means for setting the brakes automatically a valve C, two conduits 52 and 52^b leading to said valve C, the conduit 52 being supplied with air from valve H^e when the latter is operated by the engineer, an eliminating valve for cutting off air pressure supply to the automatic brake applying means to eliminate the function thereof, a conduit 52^a for supplying air from valve C to the said eliminating valve, a speed governor controlling the position of the valve C to connect conduit 52 with pipe 52^a when the engine is running at a prescribed speed and to connect conduit 52^b with conduit 52^a when the speed is lowered, and a valve for controlling the conduit 52^b said valve being operable by the engineer, timing means operated by air for holding valve 58 open for a prescribed period, and a valve operated by the engineer at the time valve 58 is operated to supply air pressure to the said timing means.

50 12. In combination in an air brake system
an automatic brake valve to be operated by
the engineer for applying the brakes, auto-
matic brake applying means, an eliminating
valve to eliminate the function of said auto-
matic brake applying means, a speed gov-
erned valve for controlling the operation of
the eliminating valve, means for operating
the eliminating valve when the speed gov-
erned valve is set at low speed position, the
said speed governed valve permitting the
operation of the automatic brake valve to
operate the eliminating valve when the speed
of the train is above a prescribed limit and an
air release valve controlled by the governor
60 for releasing the air to set the brakes when
65

the speed of the train exceeds a certain limit, substantially as described.

13. In combination an engineer's automatic
brake valve which when operated will apply
the brakes, automatic brake applying
means to set the brakes, an eliminating valve
for eliminating the function of the automatic
brake applying means, a connection for sup-
plying air pressure to said eliminating valve
for setting the same when the engineer's auto-
matic brake valve is operated, an independ-
ent hand operable device for supplying air
pressure to the eliminating valve to set it in
eliminating position, a speed governed valve
controlling the connections between the said
independent hand operable device and the
engineer's automatic brake valve and the
eliminating valve, a valve operated by the
independent hand operable device for sup-
plying air pressure through the speed gov-
erned valve when this is set in low speed posi-
tion, timing means controlling the period of
operation of the last named valve, said timing
means being operable by air pressure
and a valve controlled by the independent
hand operable device for supplying air pres-
sure to the timing means, substantially as
described.

14. In combination in train stop mechanism, means automatically operated by air pressure for setting the brakes, an engineer's valve controlling air pressure for recharging the train pipe and releasing the brakes, and a disabling valve to prevent the engineer from recharging the train pipe until after a prescribed period of time has elapsed, said disabling valve comprising two members, seats therefor, one of said members seating in the direction of air pressure from the engineer's valve and the other member seating in the direction of air pressure from the train pipe, and means operated by air pressure for seating the valve members to disable the engineer's valve when the brakes are set, substantially as described. 110

15. In combination in train stop mechanism, means automatically operated by air pressure for setting the brakes, an engineer's valve controlling air pressure for recharging the train pipe and releasing the brakes, and a disabling valve to prevent the engineer from recharging the train pipe until after a prescribed period of time has elapsed, said disabling valve comprising two members, seats therefor, one of said members seating in the direction of air pressure from the engineer's valve and the other member seating in the direction of air pressure from the train pipe, and means operated by air pressure for seating the valve members to disable the engineer's valve when the brakes are set, said last mentioned means being freed from the air pressure by a bleeding action of the air therefrom after the automatic setting of the brakes has taken place, and means operated 115
120
125
130

by air pressure under the control of the engineer for opening said valve members from their seats, substantially as described.

16. In combination in train stop mechanism, means automatically operated by air pressure for setting the brakes, an engineer's valve for controlling air pressure for recharging the train pipe and releasing the brakes, a disabling valve to prevent the engineer 10 from recharging the train pipe, said valve seating in the direction of air pressure thereon, whereby it will be maintained in closed position against displacement due to vibration of the train, substantially as described.

17. In combination in train stop mechanism, means automatically operated by air pressure for setting the brakes, an engineer's valve for controlling air pressure for recharging the train pipe and releasing the 20 brakes, a disabling valve to prevent the engineer from recharging the train pipe, means for locking the disabling valve in open position, air pressure operated means for releasing the lock, for the closing of the valve, 25 means for bleeding the air pressure away to allow the valve to be opened after a prescribed period of time has elapsed, and means operated by air pressure controlled by the engineer for opening the valve, substantially as 30 described.

18. In combination in train stop mechanism, means automatically operated by air pressure for setting the brakes, an engineer's valve for controlling air pressure for recharging the train pipe for releasing the 35 brakes, a disabling valve to prevent the engineer from recharging the train pipe, said valve comprising two members for closing the pipe leading from the engineer's valve 40 to the train pipe, one seating in the direction of the pressure from the engineer's valve and the other seating in the direction of pressure from the train pipe, a rocker arm between the valves for opening them, a cylinder 45 and piston subjected to air pressure and connected with the rocker arm, a detent engaging the piston, a second piston and cylinder, an air pressure connection to the second cylinder, a port between the cylinders controlled by 50 the second piston whereby air is let into the first cylinder after the detent is released by the movement of the second piston under pressure of the air, said detent holding the second piston in its open position, means for 55 bleeding the said cylinders of air, a piston connected with the rocker arm for opening the valve members, a cylinder therefor, and means under the control of the engineer for introducing air pressure into said cylinder 60 for opening the valve members, the said detent being released from the second piston by the action of the first piston moved by the opening of the valve members, substantially as described.

19. In combination in train stop mech-

anism, means automatically operated by air pressure for setting the brakes, an engineer's valve controlling air pressure for recharging the train pipe and releasing the brakes, a disabling valve to prevent the engineer from 70 recharging the train pipe until after a prescribed period of time has elapsed, said disabling valve comprising a pair of valve members, each closing upon a seat in the direction of the air pressure exerted thereupon, springs 75 tending to hold the valve members seated, a member arranged between the stems of the valves, and means for operating the said member to open the valves against the pressure of their springs, substantially as de- 80 scribed.

20. In combination in train stop mechanism, means automatically operated by air pressure for setting the brakes, an engineer's valve controlling air pressure for recharging 85 the train pipe and releasing the brakes, a disabling valve to prevent the engineer from recharging the train pipe until after a prescribed period of time has elapsed, said disabling valve comprising a pair of valve members, each closing upon a seat in the direction of the air pressure exerted thereupon, springs 90 tending to hold the valve members seated, a member arranged between the stems of the valves, and means for operating the said 95 member to open the valves against the pressure of their springs, said member being arranged to open one of the valves in advance of the other, so that the one valve which is first opened will enable the pressure to be equalized on the rear side of the other valve in respect to the pressure tending to hold said valve closed.

21. In combination in train stop mechanism, means automatically operated by air pressure for setting the brakes, an engineer's valve controlling air pressure for recharging the train pipe, and a disabling valve comprising two valve members, one seating in the direction of air pressure from the engineer's valve and the other seating in the direction of pressure from the train pipe, and means for opening said valve members one in advance of the other to equalize the pressure upon the valve last operated, substantially as de- 105 scribed.

22. In combination in train stop mechanism, means for automatically setting the brakes by releasing air pressure, an engineer's valve to recharge the train pipe, disabling 110 valve means to prevent the engineer from recharging the train pipe, a piston forming part of the valve operating means, a cylinder, a detent for holding the piston with the valve mechanism in open position, a second cylinder having a port leading to the first cylinder for supplying air to and permitting air to bleed from the first cylinder, said second piston when operated by air pressure releasing the detent, and then uncover- 115 120 125 130

ing the said port to allow air pressure to reach the first piston, said detent then holding the second piston in its operated position, air pressure operated means for opening the valve mechanism and thereby restoring the first piston to normal position after the air pressure has bled away therefrom, said first piston operating the detent to release the second piston, and a spring for returning the second piston to normal position, covering said port, substantially as described.

23. In combination in automatic train stop mechanism, means automatically operated by air pressure for setting the brakes, an engineer's valve for recharging the train pipe for releasing the brakes, a disabling valve for preventing the engineer from recharging the train pipe until after a prescribed period of time has elapsed, means for locking the disabling valve in open position, and air pressure operated means for releasing said locking means, said disabling valve when released seating in the direction of pressure thereon, whereby said valve will be held against dislodgment from its closed position, substantially as described.

24. In combination with an eliminating valve, a speed governed valve for supplying air pressure thereto to set it in eliminating position, a valve for supplying air to the speed governed valve, a hand operable device for opening said valve, and pneumatically controlled timing means for retarding the closing of said valve for a prescribed period of time, substantially as described. 35

25. In combination with an eliminating valve, a speed governed valve for supplying air pressure thereto to set it in eliminating position, a valve for supplying air to the speed governed valve, a hand operable device 40 for opening said valve, and pneumatically controlled timing means for retarding the closing of said valve for a prescribed period of time, said timing means including a piston, a cylinder, a small air port through which 45 the air is expelled when the piston is moved by said hand operable device, said piston being restored to normal position by the inlet of air through said port, substantially as described. 50

In testimony whereof, I affix my signature.
PATRICK J. CLIFFORD.
